UNITED STATES PATENT OFFICE

WILLIAM F. HENDRY, OF OSSINING, NEW YORK, ASSIGNOR, BY MESNE ASSIGNMENTS, TO MANHATTAN ELECTRICAL SUPPLY COMPANY, INC., OF JERSEY CITY, NEW JERSEY, A CORPORATION OF NEW JERSEY

ELECTRICAL DISCHARGE DEVICE

Application filed May 19, 1927. Serial No. 192,658.

This invention relates to electrical relays and relates more particularly to electrical relays of the gaseous type.

The object of the invention is the provision of a cold electrode gas filled relay tube.

I have found that an electrical discharge passing between two cold electrodes in an attenuated gaseous atmosphere can be controlled by the insertion of a third electrode 10 and by the proper selection of electrode size and mountings. By the term cold electrode I mean an electrode that is not of the filamentary type and not supplied with heat other than the heat developed by the action 15 of the tube itself.

More specifically, I have found that an electrical discharge tube having cold electrodes can be so constructed as to be capable of use as a relay for repeating electrical signals or disturbances. Good results may be secured with such tubes when constructed with a large electrode and a small electrode. While the materials from which these electrodes are made are not necessarily limited, 25 large electrodes of aluminum and small electrodes of carbon have been found to give good results. The small electrode is mounted opposite the large electrode and is surrounded by or mounted on a disc of mica or 30 other insulating material which is capable of withstanding the heat developed by the discharge occurring in the tube. The large electrode preferably is formed into the shape of a hemisphere and positioned adjacent to 35 the mica disc, which is of approximately the same diameter as the hemispherical electrode.

As thus far described, the tube is similar to the tube disclosed in the copending application of Lewis S. Baker, Serial No. 61016, filed October 7, 1925. The present construction, however, involves the addition of a control electrode to a tube of the foregoing construction. This electrode may be in the 45 form of an annular ring and be mounted directly on the outer edge of the mica disc. The entire electrode assembly is enclosed in an envelope of glass or other material which is filled with some gas such as one of the 50 gases of the rare gas group, for example,

neon or helium, at low pressure. This pressure may be of the order of a few millimeters of mercury, for example, in the neighborhood of two to ten millimeters.

I have found that when current is passed 55 between the two main electrodes of a tube constructed in accordance with the foregoing disclosure, by means of an alternating current source of fairly high potential, the current passing through the tube is rectified and 60 limited to a certain value.

According to this invention, I have found that if the third electrode be grounded the current through the tube will immediately be increased in value by a relatively large 65 amount. This ground need not be an extremely low resistance ground, but on the contrary may be an extremely high resistance ground. For example, I have found that if the lead-in wire attached to the third 70 electrode be touched by the hand of a person, the current through the tube will immediately be increased. This result also can be secured in many cases merely by touching the lead-in wire of a third electrode to the 75 table on which the tube operating apparatus is positioned.

While I have described the above mentioned tube as having the third electrode mounted on the mica disc, it need not necessarily be mounted there as the tube will also function successfully if the third electrode be made of wire gauze and be positioned between the mica disc and the large electrode. The wire gauze may be flat and parallel with the mica disc or it may be made in hemispherical form similarly to the large electrode. Likewise, the large electrode need not necessarily be hemispherical as a flat electrode may be used likewise. I have found also that a tube can successfully be constructed wherein both electrodes are of the same size. In such a tube each of the electrodes may be mounted on a mica disc or be surrounded by a mica annulus, and be positioned opposite each other a suitable distance apart, with a gauze electrode mounted between the two electrodes. I have found that the disc electrodes may be made, for example, 90 of carbon in the form of a short cylinder of

fairly large diameter. These electrodes would be mounted in a gaseous atmosphere similar to that described above. With this type of tube the main source of potential should be applied between the two large electrodes.

I have found in connection with tubes of this general construction that a control of the current between the two main electrodes can be secured by placing a bias potential on the third electrode, for example, by placing a battery between it and one of the main electrodes. Likewise by placing a source of signal energy between the third electrode and one of the main electrodes, a control of the current through the main electrode circuit, responsive to the signal current, can be secured. In the first type of tube which I mentioned above, the control circuit preferably would be inserted between the third electrode and the small electrode.

While the mode of operation of the tubes I have described is not absolutely clear as yet, I advance the following theory, if not the correct one, a possible one, which seems to be substantiated by various tests and the actions of the tubes.

During the operation of the tube on alternating current a space charge is built up around the anode, which space charge extends to the mica disc and imparts a charge to it. This charge is positive and serves to attract electrons during the operation of the cycle when the small electrode is negative, thus reducing the migration of electrons between the two main electrodes and which results in a decrease in current flow between the two main electrodes. By placing a metal ring on the mica disc and connecting the ring to ground, the positive charge upon the disc is dissipated and upon dissipation of the charge current flow between the two main electrodes is increased. Likewise the charge on the disc can be varied by a biasing potential applied between the ring and one of the main electrodes, which would result in a change in current flow between the two main electrodes. It appears that this static charge also can be dissipated by placing a metal ring adjacent to, but not touching the insulating disc. Other objects and advantages of the invention will appear more clearly from a consideration of the following description taken in connection with the accompanying drawings.

In the drawings, Fig. 1 illustrates a tube constructed in accordance with my invention wherein a large hemispherical electrode and a small button electrode are employed.

Fig. 2 illustrates a circuit arrangement for the tube shown in Fig. 1.

Fig. 3 represents a modification of the tube shown in Fig. 1.

Fig. 4 illustrates a circuit arrangement for the tube shown in Fig. 3.

Fig. 5 illustrates an embodiment of my invention wherein two electrodes of the same size are used.

Figs. 6 and 7 illustrate circuits for use with the tube illustrated in Fig. 5.

In Fig. 1 reference numeral 1 indicates an envelope of glass or other suitable material wherein are mounted two electrodes 2 and 3 respectively. Electrode 2 is attached to a lead-in rod 6 which passes through a glass sleeve 8, which sleeve in turn is attached to the envelope 1. Lead-in rod 6 is attached to wire 12 which is sealed through the envelope 1. Electrode 2 is supported in similar fashion by a lead-in rod 7 which passes through a glass sleeve 9 which is attached to envelope 1. Lead-in rod 7 communicates with the exterior of the glass envelope by means of a lead-in wire 10. Positioned underneath electrode 3 is a mica disc 4, this disc being held between the electrode 3 and the glass sleeve 9. Mounted upon mica disc 4 is an annular electrode, or grid 5 which communicates with the exterior of the glass envelope by means of a lead-in wire 11.

Within the envelope 1 is a filling of rare gas at low pressure. The electrodes 2 and 3 are preferably made of aluminum and carbon respectively, but other materials may be used with but slightly different results. Copper or iron might be substituted for the aluminum electrode and nickel or the like might be used in place of carbon. While a filling or rare gas such as neon is preferable for best results, other gases or mixtures of gases may be used.

In Fig. 2 the main circuit, which will hereinafter be referred to as the plate circuit, is between electrodes 2 and 3, through load 18 and battery 17. The control or grid circuit is between electrodes 3 and 5 through battery 20 and key 19. Shunted around the contacts of key 19 is a condenser 21 which serves to reduce sparking at the contacts of the key 19.

It is to be understood that alternating current may be used in place of battery 17, if desirable, for certain types of work, as the action of the control electrode will also regulate the flow of alternating current in the plate circuit similarly to direct current.

Fig. 3 represents a tube substantially similar to that shown in Fig. 1 except that the control electrode 5 is positioned between the large and small electrodes and is supported by a mica disc 13, which is in turn secured by three posts 14 which are mounted upon mica disc 4.

In Fig. 4 the plate circuit includes electrodes 2 and 3, load 18 and battery 17, while the control circuit consists of electrode 5 which is connected to a key 19 which has one contact connected through to ground.

In Fig. 5 two electrodes 15 and 16 of equal size are mounted upon mica discs 4 which are

supported substantially the same as electrode 3 of Fig. 1. Positioned between the two electrodes is the control electrode 5 which consists of a wire screen mounted on a mica annulus 13. The mica annulus 13 is supported between mica discs 4 by means of posts 14.

In Figs. 6 and 7 the plate circuit consists of electrodes 15 and 16, load 18 and battery 17, while the control circuit comprises battery 20, key 19 and electrodes 5 and 15. Condenser 21 is shunted around the contacts of key 19 for the purpose of preventing excessive sparking. This condenser need not necessarily be included as the circuit will function very well without it. The diagram of Fig. 7 is substantially the same as that shown in Fig. 6 except that the polarity of battery 17 is reversed.

The operation of the device shown in Figs. 1 and 2 is as follows: Battery 17 supplies current which causes a discharge between electrodes 2 and 3. This discharge is limited to a certain value for any given potential of the control electrode 5. When the key 19 is closed the potential of the battery 20 is applied to electrode 5 which causes a change in the flow of current between electrodes 2 and 3. While the circuit is shown as having battery 20 biasing the third electrode 5, the circuit will work excellently without the battery. When no battery is used it is necessary merely to connect the lead-in wire of electrode 5 to ground, when immediately the current flow between the two electrodes 2 and 3 will be increased greatly. The connection to ground need not be of a low resistance, but may be of an extremely high resistance as it has been found, for instance, that the conductivity offered by the human body is sufficient to cause a marked change in the value of the current flowing between electrodes 2 and 3. Likewise it has been found that a similar effect can be secured by touching the leading-in wire of electrode 5 to the table upon which the tube 1 and its associate circuits are supported. It seems probable also that such an effect would be secured without any further connection than the surrounding atmosphere if the atmosphere were damp, for example. In place of the key 19 might be placed the secondary of a transformer, a microphone or the like, in which event the tube might be used to amplify electrical disturbances of any kind. The tube, as shown in Fig. 1 is so extremely sensitive that a very small change in resistance of the circuit between electrode 5 and electrode 3 will cause a very marked change in current between the two main electrodes. This phenomenon might be made use of in many and varied ways, for example, the device might be used as a very sensitive burglar alarm by connecting a wire from electrode 5 to the knob of a door or other metal object or placing it in some position where an unacquainted person

would come in contact with it, which contact would cause a current to flow between the main electrodes and through load device 18 and cause a bell to be rung or other signal to be actuated.

Because of the peculiar operating characteristics of this tube a very minute potential change in the control circuit will cause a large change of current in the main circuit. With proper conditions this change is extremely violent. For example, when the electrode 5 is left disconnected and the potential of battery 17 is such that electrode 2 is positive with respect to electrode 3, if the potential of the battery be properly regulated practically no current will flow between electrodes 2 and 3. However, immediately upon the grounding of electrode 5 through a resistance even as high or higher than that of the human body the current through the main electrodes immediately increases to a relatively large amount. The tubes and circuits illustrated in the remaining figures all operate in substantially the same manner and hence it is believed unnecessary to go into a detailed explanation thereof. In connection with a particular tube such as shown in Fig. 5, it might be said that with the batteries connected as shown in Fig. 6 that the current in the plate circuit varies in a straight line ratio with respect to a change of potential of battery 20. For example, it was found that with battery 17 having a potential of 500 volts and battery 20 having a potential of 270 volts, connected with the positive terminal to the control electrode 5, that the current in the main electrode circuit was ten milliamperes, while with the potential of battery 20 at 270 volts, with the negative terminal connected to electrode 5, the main electrode current was 47 milliamperes. With battery 20 connected between electrodes 5 and 16 it was found that with the potential of battery 17 at 495 volts and that of battery 20, 112 volts, with the negative terminal connected to electrode 5, that the plate current was 1.65 milliamperes; while with the potential of battery 20 equal to 125 volts and the positive connected to electrode 5, a plate current of 3.3 milliamperes was obtained. With a tube of the type shown in Fig. 3 it was found that the current through the plate circuit varied directly in proportion to the potential of the control electrode 5 up to a certain value, when a point was reached where further increase in the potential of the electrode 5 did not cause a corresponding change in the main electrode current. Such a tube would therefore be suitable for the detection of certain types of signals, for example, such as those used in radio.

It will be obvious to those skilled in the art that the invention is capable of a wide variety of modifications and adaptations and that the present disclosure is intended merely to il-

lustrate its nature without limiting its scope
which is defined in the appended claim.

What I claim is:

5 In an electrical discharge device, a gas filled envelope, a hemispherical cathode in said envelope, an anode in said envelope mounted at a point substantially equidistant from all points of said cathode, leading-in wires for said anode and cathode, an insulating disc of
10 substantially the same diameter as said cathode held below said cathode, and an annular control electrode positioned on said disc.

In testimony whereof, William F. Hendry has signed his name to this specification this
15 17th day of May, 1927.

WILLIAM F. HENDRY.
